(57) **CLAIM**

The ornamental design for a round plate with concentric compartment and two side compartments, as shown and described.

DESCRIPTION

FIG. 1 is a perspective view of a round plate with concentric compartment and two side compartments showing our new design;

FIG. 2 is a top plan view thereof;

FIG. 3 is a side elevation thereof;

FIG. 4 is a cross-sectional view thereof taken along line 4—4 of FIG. 2; and,

FIG. 5 is a partial cross-sectional view thereof taken along line 5—5 of FIG. 2 and drawn on a slightly enlarged scale.
